De Witt, N.Y.

Filed Apr. 26, 1961, Ser. No. 64,917

Term of patent 3½ years

(Cl. D1—12)

FIG. 1

FIG. 3

FIG. 1 is a front elevational view of an advertising sign for a dry cleaner or the like showing my new design, the rear being a mirror image of the front shown;

FIG. 2 is a cross-sectional view thereof taken on line 2—2 of FIG. 1; and

FIG. 3 is a fragmentary top plan view thereof, a portion of the center panel and its base being omitted for convenience of illustration.

I claim:

The ornamental design for an advertising sign for a dry cleaner or the like, as shown and described.
